UNITED STATES PATENT OFFICE.

CHARLES THOMAS MASON, OF SUMTER, SOUTH CAROLINA, ASSIGNOR TO SPLITDORF ELECTRICAL COMPANY, OF NEWARK, NEW JERSEY, A CORPORATION OF NEW JERSEY.

METHOD AND APPARATUS FOR IGNITING THE CHARGE IN INTERNAL-COMBUSTION ENGINES.

1,299,592.

Specification of Letters Patent.

Patented Apr. 8, 1919.

Application filed November 9, 1917. Serial No. 201,114.

To all whom it may concern:

Be it known that I, CHARLES THOMAS MASON, a citizen of the United States, residing at Sumter, in the county of Sumter and 5 State of South Carolina, have invented certain new and useful Improvements in Methods and Apparatus for Igniting the Charge in Internal-Combustion Engines, of which the following is a specification, reference being had to the accompanying drawing.

My invention relates to a method and apparatus for igniting the charge in internal combustion engines, and has for its objects 15 the provision of an ignition system wherein a high tension magneto is employed capable of producing sparks of equal intensity for the various cylinders of the engine; the provision of an ignition system in which the 20 magneto may be employed in connection with an engine having its cylinders arranged in groups and at an angle from the vertical in relation to the crank shaft; and the provision of a system wherein the maximum 25 amount of flux available from the permanent magnets employed is utilized. Ancillary objects will more fully hereinafter appear.

My invention consists more in the principle of design or the method of producing 30 ignition, than in the actual mechanical arrangement of the parts of the magneto, as numerous arrangements will be obvious to those skilled in the art. All such arrangements will, however, embody the principle 35 of design which I claim as new.

The accompanying drawings show one form of magneto adapted for use in this system, but it will be understood that the herein disclosed type is selected merely for the 40 sake of illustration and I am not confined to it.

The magneto illustrated is of the well known Dixie type, the principle of which is described in reissue patent to me, No. 14,373, 45 dated October 2d, 1917. In the said patent, the main elements of the magneto comprise a permanent field magnet having a rotor axially aligned with its poles, and a current-generating coil with two pole pieces, each 50 having a radial face lying adjacent the path of travel of the rotor. The present system employs substantially the same arrangement of the elements constituting the machine,

with certain important modifications in the design of the rotor and the pole pieces of the 55 generating coil.

In the accompanying drawings, in which like letters and figures of reference denote the same parts wherever they are shown,

Figure 1 is a view partly in cross section 60 of a magneto embodying the method of construction constituting my invention;

Fig. 2 is a view partly in cross section at right angles to Fig. 1; and

Fig. 3 is a diagram of the complete ignition system for a multicylinder motor with the cylinders set at an angle, such as used 65 for aeronautic purposes.

In magnetos of the general type in which a rotor having portions of permanent and 70 opposite polarity are employed, the said rotor has heretofore usually had one and sometimes two horns or lobes of the same polarity, and has, therefore, been adapted to give two or four equally spaced impulses or 75 peaks of current per revolution. The present system being intended for use in multi-cylinder engines with the cylinders set at an angle, several peaks of current or sparks per revolution are required, and for the sake of 80 illustration the following description is given of the system adapted for use with a twelve-cylinder engine.

The numeral 1 denotes a permanent magnet suitably supported upon the base 2 of the 85 machine. In suitable end plates 3 and 4 are journaled the shafts 5 and 6 of the rotor, comprising the members 7 and 8. These members are separated by a non-magnetic block 9, so that 7 really constitutes a revolving extension of the pole "N" of the magnet, and 8 a revolving extension of the pole "S." The member 7 is provided in the case of a magneto for twelve-cylinder engines, with a 90 plurality of lobes or prongs designated N¹ to N⁶ inclusive, and the member 8 with a series of prongs S¹ to S⁶ inclusive. The ends of these prongs or lobes extend toward the center of the machine and are adapted to rotate in front of the pole pieces P, P. The 100 pole pieces P, P are provided with a plurality of inwardly extending faces, P¹ to P⁶ inclusive, thereby forming a plurality of flux paths from the rotor through the core Q carrying the generating windings.

I consider one of the important features

of my invention to be the provision of a plurality of extensions (P^1 , P^2 , etc.), for each pole piece and the provision of a plurality of lobes (N^1 , N^2 , etc.), for each member of the rotor.

Referring now to magnetos previously known, it will be noted that the pole pieces of these magnetos having only one polar face adjacent the rotor, that if, for the purpose of obtaining sparks at angular or irregular intervals, the rotor was subdivided as just described, the cross section of the lobes had to be greatly lessened, as well as the width of the polar face of the pole pieces, with the result that a very weak spark would be obtained, because of the small area of the opposed flux-gathering surfaces.

It will be observed that by my method of increasing the number of faces in each pole piece, (which may be termed a delta form of construction) and opposing to each polar face a rotor lobe, that the total amount of opposed surface between rotor and pole pieces is substantially equal to that obtained with the single lobe machines shown in the prior art, and the magnetic break between the large number of pole faces is greater than in the single lobe machines, resulting in a magneto that will generate at a lower initial speed.

Considering the rotor to be turning from left to right, Fig. 3, lobe N^1 breaks from the pole face P^1 , and simultaneously N^6 breaks from P^2 , and N^5 breaks from P^3 , while lobes S^6 , S^5 and S^4 make on P^1 , P^2 and P^3 respectively. On the other side, S^1 breaks from P^4 , S^2 from P^5 and S^3 from P^6 , while N^1 , N^2 and N^3 make on P^4 , P^5 and P^6 respectively.

When the lobes break and open away from the respective pole faces about $.020''$, the cam C presents a lobe or high side against the fiber block F of the interrupter mechanism, thereby opening the platinum points X and Y, and interrupting the primary circuit at the peak, allowing magnetism to pass through the pole pieces P, P and through the core Q, thereby producing a high tension current in the secondary windings at the proper time, the interrupter opening for each peak with the break at the pole pieces uniform, so that all sparks are of the same intensity.

In a magneto of the foregoing description, the shaft 5 will be driven at twice engine speed, with the result that magnetic waves, impulses or peaks will be obtained fifteen degrees apart relative to the engine. The interrupter mechanism, which may be of any suitable mechanism, and which is merely indicated diagrammatically in Fig. 3, is driven at engine speed by means of the gear H mounted on the rotor shaft 6, which meshes with the gear J which drives the cam C at one-half speed of shaft 5; therefore

the interrupter mechanism runs at engine speed. The cam C may be designed to operate the interrupter to produce sparks at any odd or even multiple of fifteen degrees. In the present example, the spark should occur at $45-75-45-75$, so the following sequence of events takes place.

A spark is made by lobe C' on cam C opening points $x-y$ as rotor lobes N^1 , N^6 and N^5 break from P^1 , P^2 and P^3 respectively, (disregarding the S side of the machine).

S^6 now passes P^1 , but no spark is produced, as there is no corresponding lobe on cam C to open points $x-y$. N^6 now passes P^1 but no spark is produced.

S^5 now passes P^1 and a spark is produced because lobe C^2 on cam C opens points $x-y$.

The distance from C^1 to C^2 over the cam C represents one short interval, the distance from C^2 to C^3 a long interval, from C^3 to C^4 a short interval, etc. It will be observed that the flux waves generated when block F is between the points C^1 , C^2 , etc., are not utilized, but are re-pressed as sparks are not needed.

The high tension distributor in this particular case is mounted upon the engine and runs at half engine speed. The segments are $\frac{4}{2} \frac{7}{2} \frac{4}{2}$, etc., or $2\frac{1}{2}-3\frac{1}{2}-2\frac{1}{2}$, and so on. The secondary connection 10 connects to a high tension terminal or cable 11, which is connected to the rotating element D of the distributor. The distributor may be of any suitable type, and in the arrangement shown in Fig. 3, the brush T is connected to D and rotates within the casing, thereby distributing to the segments D^1 , D^2 , D^3 , etc., suitably placed at the proper angles and arranged to connect to the spark plugs indicated at 12.

The primary circuit of the magneto is indicated at 13, the secondary at 14. The primary circuit is completed through the framework of the machine denoted at G. A condenser K is connected across the primary circuit in the usual manner. I have not described the construction of the magneto in detail, as details not specifically described are already well known.

From the foregoing description it will be seen that the essential features of my invention consist in providing the pole pieces of the magneto with a plurality of faces, and in providing the rotor with a plurality of horns or prongs, thereby obtaining large opposed surfaces permitting the maximum amount of magnetic flow, and at the same time obtaining maximum breaking surface. This method also contemplates the arrangement of the polar faces, so that sparks of equal intensity may be obtained at odd or even multiples of a certain predetermined figure, which in the example here shown is fifteen degrees measured on the engine shaft.

The advantage of this is that it enables uniform sparks to be obtained without making the rotor asymmetric or in any manner distorting the core pole pieces.

5 While I have here shown a magneto in which each pole piece has three faces, and each rotor member has six lobes, it will be understood that I do not confine myself to such an arrangement, as it is obvious that 10 for some engines, each rotor member would have only three lobes, and each pole piece only two faces, such as P^1 and P^3 . This would depend on the number and arrangements of the cylinders or upon the driving 15 speed of the magneto.

It will be observed that, in any case, the magneto will have two polar extensions for the care of the generating windings, these extensions surrounding the rotor, and each 20 extension having a plurality of polar faces, the distance between the polar faces on either of the extensions being greater than the combined thickness of any two adjacent prongs of the rotor.

25 It will be observed that by varying either the speed of the magneto, or the number of lobes on the rotor members, or both, that almost any desired combination of spark-timing can be obtained. The number of 30 faces on each pole piece is also varied as desired.

The machine herein described is arranged for "fixed ignition," no provision being made for advancing and retarding the time 35 of the spark in relation to the engine pistons. If it is desired to supply a machine for a system wherein the timing of the spark must be varied, it is merely necessary to make the interrupter mechanism movable on its support and advance or retard it in increments of fifteen degrees, thereby always keeping the spark at the same intensity, advance or retard, as the points $x-y$ will always open on the peak. As such movable interrupter 40 mechanisms are already well known in the art, and as the mechanical construction necessary forms no part of this invention, I do not herein describe the same. In some cases the high tension distributor would be 45 mounted directly upon the magneto, as shown in my Patent 1,229,045, dated June 5th, 1917, and the generating coil may be movable for timing purposes as therein described.

50 Having thus described my invention, what I claim as new and desire to secure by Letters Patent, is:

1. The method of generating ignition current for internal combustion engines which 60 consists in providing a primary magneto motive force, shifting the flux thereof in a symmetrical figure by means controlled by the movement of the engine, collecting the flux from said shifting means through a plurality of paths, and conducting the flux so

gathered through a core carrying generating windings.

2. The method of generating ignition current for internal combustion engines, which consists in providing a primary magneto 70 motive force, shifting the flux thereof in a symmetrical figure by means controlled by the movement of the engine, collecting the flux from said shifting means through a plurality of paths, passing the flux so collected 75 through a core carrying generating windings, and interrupting the current so generated for supplying timed sparks.

3. The method of generating ignition current for internal combustion engines, which 80 consists in providing a primary magneto motive force, shifting the flux thereof in a symmetrical figure by means controlled by the movement of the engine, collecting the flux from said shifting means through a 85 plurality of paths, passing the flux so collected through a core carrying generating windings, and interrupting the current so generated at its maximum peak for supplying 90 sparks.

4. The method of generating ignition current for internal combustion engines which consists in providing a primary magneto 95 motive force, shifting the flux thereof in a symmetrical figure by means controlled by the movement of the engine, collecting the flux from said shifting means through a plurality of paths, conducting the flux so gathered through a core carrying generating windings, interrupting the current so generated for supplying sparks, said interruptions occurring at long and short increments of time, corresponding to the timing requirements of the engine.

5. The method of generating ignition current for internal combustion engines which 105 consists in providing a primary magneto motive force, shifting the flux thereof in a symmetrical figure by means controlled by the movement of the engine, collecting the 110 flux from said shifting means through a plurality of paths, conducting the flux so gathered through a core carrying generating windings and interrupting the circuit through said windings at intervals corresponding to the ignition timing of the engine.

6. The method of generating ignition current for internal combustion engines which 120 consists in providing a primary magneto motive force, shifting the flux thereof in a symmetrical figure by means controlled by the movement of the engine, collecting the flux from said shifting means through a 125 plurality of paths, conducting the flux so gathered through a core carrying generating windings and interrupting the circuit through said windings at long and short intervals corresponding to the ignition timing of the engine.

7. The method of generating ignition current for internal combustion engines, which consists in providing a primary magneto motive force, shifting the flux thereof in a symmetrical figure by means controlled by the movement of the engine, intermittently completing and reversing the path of flux through a flux-receiving circuit having flux-gathering members of delta form, an ignition current generating coil adapted to be acted upon by said flux-receiving circuit, and means for interrupting the circuit through said generating coil in fixed timed relation to the peaks of current generated.
8. The method of generating ignition current for internal combustion engines, which consists in providing a primary magneto motive force, shifting the flux thereof in a symmetrical figure by means controlled by the movement of the engine, intermittently completing and reversing the path of flux through a flux-receiving circuit having flux-gathering members of delta form, an ignition current generating coil adapted to be acted upon by said flux-receiving circuit, and means for interrupting the circuit through said generating coil at odd and even intervals in fixed timed relation to the peaks of current generated.
9. In an ignition dynamo, a U-shaped magnet, an armature structure positioned between the ends of said magnet, two groups of laminations in said structure, each group forming three circumferential oppositely positioned pole shoes, and a rotor between said groups of laminations having a plurality of horns or prongs always of the same polarity.
10. The method of firing a twelve-cylinder forty-five degree four-cycle internal combustion engine, which consists in providing a primary magneto motive force, shifting the flux thereof in a symmetrical figure by means controlled by the movement of the engine, collecting the flux from said shifting means through a plurality of paths, driving said element at twice engine crank shaft speed, repressing a number of current impulses and distributing to the engine cylinders the non-repressed or working impulses in asynchronous periods corresponding to the firing periods of the engine.
11. In an ignition dynamo, a magnet, a rotor comprising magnetic inductor elements in magnetic relation to the poles of said magnet, a current generating coil, a core for said coil having pole pieces, each pole piece having a plurality of faces adjacent the path of travel of said rotor.
12. In an ignition dynamo, a magnet having poles spaced apart, a rotor journaled to turn adjacent said poles and extending longitudinally from pole to pole of the magnet and having suitable bearing supports and comprising a pair of axially separated magnetic members of permanent and opposite polarity, each member having a plurality of horns or prongs, a current generating coil, a core therefor, and pole pieces for said core, each pole piece having a plurality of pole faces adjacent the path of travel of said rotor.
13. In an ignition dynamo, a magnet, a rotor having a pair of separated magnetic members, each member having a plurality of horns or prongs, pole pieces adjacent the path of travel of said rotor, each pole piece having a plurality of flux gathering pole faces, each one of said faces being adapted to span one of the rotor prongs, and a core carrying generating windings bridging said pole pieces.
14. An ignition dynamo comprising field and coil carrying structures, a rotor having its axis passing through the poles of the field structure, a plurality of pole pieces carried by said coil structure and having a common core, and a plurality of horns on the rotor having the same polarity and adapted to bridge the pole pieces not connected to the opposite ends of said core.
15. An ignition dynamo comprising field and coil carrying structures, a rotor having its axis passing through the poles of the field structure, a plurality of pole pieces carried by said coil structure and having a common core, and a plurality of horns on the rotor having the same polarity and adapted to simultaneously bridge all of the poles connected to one end of the core.
16. In combination with an internal combustion engine, a magneto having a rotor, said rotor having a plurality of horns of the same polarity, the horns projecting from one end of the rotor being arranged intermediate the horns projecting from the other end of the rotor, a coil carrying structure carrying windings, said coil carrying structure having two polar extensions each having a plurality of pole faces, the distance between which is greater than the combined thickness of two adjacent prongs on the rotor.
17. In combination with an internal combustion engine, a magneto having a rotor driven at twice engine speed, said rotor having a plurality of horns of the same polarity, the horns projecting from one end of the rotor being arranged intermediate the horns projecting from the other end of the rotor, a coil carrying structure carrying windings, said coil carrying structure having two polar extensions each having a plurality of pole faces the distance between which is greater than the combined thickness of two adjacent prongs on the rotor, said pole faces and prongs being so disposed as to produce magnetic waves in the coil carrying structure fifteen degrees apart relative to the engine crank shaft, an interrupter mechanism driven in synchrony.

- nism with the engine and adapted to operate in synchronism with the peak of the magnetic waves produced and a high tension distributor driven at half the speed of the engine and adapted to distribute the generated current to the cylinders of the engine in timed relation with the production of said magnetic waves and the operation of said interrupter.
- 10 18. In combination with an internal combustion engine, a magneto generator adapted to produce ignition currents, said generator, having a magnetized rotor driven in timed relation to the engine and having more than three prongs or horns of each polarity,
- 15
- two pole pieces in the magneto, each pole piece having a plurality of flux gathering faces, each face adapted to engage one of the rotor horns, a core connecting the free ends of said pole pieces and adapted to carry all of the flux gathered by all of the polar faces of said pole pieces, and interrupter mechanism adapted to be driven in timed relation with said rotor, whereby some of the flux impulses produced in said core may be utilized for ignition purposes and others repressed.

In testimony whereof I hereunto affix my signature.

CHARLES THOMAS MASON.
